CELLULAR CARTON

William H. Allen, Teaneck, N. J., assignor to
 United Board & Carton Corporation, New York,
 N. Y., a corporation of New Jersey

Application January 20, 1948, Serial No. 3,242

10 Claims. (Cl. 229—28)

1

This invention relates to cellular cartons such as are employed for packaging eggs or the like.

It has for its object the provision of such a carton that can be made of a single blank of material such as cardboard and can be glued simply and inexpensively in the flat to form a carton blank which can then be opened up and assembled easily for filling.

A further object of the invention is to provide such a carton in which the eggs or other objects which are packaged are supported in such a way as to provide adequate cushioning to minimize breakage with the least material and the simplest assembly.

These objects are obtained by the carton illustrated in the accompanying drawings, in which:

Fig. 1 is a perspective view of the assembled carton;

Fig. 2 is a side elevational view of the carton partly in section showing the arrangement of the cross partitions;

Fig. 3 is an end elevational view of the carton;

Fig. 4 is a top plan view of the carton blank showing the scoring and cutting thereof;

Fig. 5 is a top plan view of the carton blank folded as in the first step of final assembly;

Fig. 6 is an end view taken from the line 6—6 of Fig. 5.

The carton blank indicated generally at 1 is made up of a top portion 2 from which depends a fastening flap 3 provided with hook members 4, side walls 5 and 6, a bottom and lower central partition-forming section consisting of bottom partition sections 7 and 8 and bottom-forming members 9 and 10. There is also provided an upper cross partition and upper central partition-forming section comprising partition-forming sections 11 and 12 and the cross partition-forming sections 13 and 14. There is also a securing flap 15.

There is a line of scoring 16 between the top 2 and the fastening flap 3, on which the material is bent for assembly. There are also lines of scoring 17, 18, 19, 20, 21, 22, 23, 24, 25, 26 and 27 between the various sections on which the material is bent either during assembling or setting up the carton.

The sections 13 and 14 are cut in a conventional manner, as shown at 28 and 29, to form cross partitions 30 and 31, which swing down-

2

wardly, as shown in Fig. 1, and engage the bottom of the assembled carton to form cells to receive the eggs or the like.

The partition sections 7, 8, 11 and 12 form the central partition 32 of the finished carton. These pairs of partition sections 7, 8, and 11, 12, are hinged together along score lines 20 and 25, respectively. In the assembled carton they lie face to face with their hinge lines adjacent and parallel.

The pairs of partition sections are joined together by attachment extensions 33 and 34, which are identical in size and shape. These attachment extensions are cut out of one of each pair of partition sections with the cuts 35, 36, 37, 38, 39 and 40 adjacent the points of hinging of said pairs of sections, namely, the score lines 20 and 25. They project in the plane of the section of which they form an extension. In the assembled carton the extension 34, which lies in the plane of partition section 12, extends into the cut-away portion of partition section 7 which is formed by the cutting-out and removal from said partition section of the attachment extension 33. Because the attachment extensions 33 and 34 are of the same size and shape, the attachment extension 34 fits into and fills the cut-away portion where it is glued. The extension 33 likewise fits into the cut-out portion left by cutting out and removing the extension 34 from the partition section 11 and is glued in this position. Thus the various partition sections are joined to form a continuous rigid central partition 32.

By properly proportioning the upper and lower partition sections and the other sections, it is possible to give the carton the form shown with the bottom sections 9 and 10 slanting upwardly to the center partition from the walls 5 and 6 as best seen in Figs. 1 and 3, thus providing adequate cushioning for the contents of the carton. The partition constructed as shown assures the maintenance of this form. To further assure against downward collapse of the bottom member there are provided extension foot members 41 and 42, which form downward extensions from the lower partition sections 7 and 8 and which are cut out of the bottom members 9 and 10 adjacent the score lines 19 and 21.

In assembling the carton, the first step is to fold the blank to the position shown in Fig. 6,

folding along the lines of scoring 20, 21, 23 and 25. This brings the attachment extensions 33 and 34 to the assembled position and joins all of the partition sections 7, 8, 11 and 12 into a single partition. Prior to the folding appropriate applications of glue are made so that the attachment extensions 33 and 34 are fastened in position.

Thereafter, the carton is folded on the score line 19, which brings the securing flap 15 adjacent the upper portion of the wall 5; an appropriate application of glue having been made, this results in the complete gluing of the carton.

The carton remains in this form during shipping and only when it is desired to fill the carton is it erected. This is done by swinging the parts to the position shown in Figs. 1, 2 and 3. The carton is first opened up and the partitions 30 and 31 are pushed downwardly, where they frictionally engage the bottom-forming sections 9 and 10. The end partitions fit into appropriate slots 43 and are thus anchored to prevent loss of eggs or the like from the ends of the carton.

With the construction shown and described, it is possible to assemble the carton with a minimum of gluing, and the central partition 32 is rigid and serves to hold the carton in assembled set-up position, with the bottom sections raised above the bottom line of the carton to provide adequate cushioning for the contents of the carton.

A single form of the carton has been described. It will be apparent, however, that modifications thereof can be made without departing from the invention. The preferred form of the carton has been illustrated or shown, but by way of illustration only and not by way of limitation. It is intended to be limited only by the claims.

I claim:

1. A cellular carton comprising a continuous bottom and lower central partition-forming portion comprising a pair of lower partition sections disposed face to face and hinged together at their upper edges, one of said lower partition sections having an attachment extension thereon cut out of the other of said lower partition sections adjacent the point of hinging of said sections and projecting upwardly in the plane of its section; a bottom section hinged to the lower edge of each of said lower partition sections and hinged at its opposite edge to a carton wall member said lower partition sections extending upwardly from the bottom sections; and a continuous cross partition and upper central partition-forming portion comprising a pair of upper partition sections disposed face to face and hinged together at their lower edges, one of said upper partition sections having an attachment extension thereon cut out of the other of said upper partition sections adjacent the point of hinging of said sections and projecting downwardly in the plane of its section and being identical in size and shape with the upwardly extending attachment extension of the lower partition sections, said upper and lower partition sections forming a central partition with the hinge line between said upper partition sections extending parallel to and adjacent the hinge line between said lower partition sections; a cross partition section hinged to the upper edge of each of said upper partition sections and hinged at its opposite edge to a carton wall member said upper partition extensions extending downwardly from the cross partition sections, the attachment extensions from the upper and lower partition sections being disposed on

opposite sides of the central partition and each disposed directly opposite and fitting in the portion of the opposed partition section from which the other attachment extension was cut and fixed therein.

2. A cellular carton comprising a continuous bottom and lower central partition-forming portion comprising a pair of lower partition sections disposed face to face and hinged together at their upper edges, one of said lower partition sections having an attachment extension thereon cut out of the other of said lower partition sections adjacent the point of hinging of said sections and projecting upwardly in the plane of its section; a bottom section hinged to the lower edge of each of said lower partition sections and hinged at its opposite edge to a carton wall member said lower partition sections extending upwardly from the bottom sections; and a continuous cross partition and upper central partition-forming portion comprising a pair of upper partition sections disposed face to face and hinged together at their lower edges, one of said upper partition sections having an attachment extension thereon cut out of the other of said upper partition sections adjacent the point of hinging of said sections and projecting downwardly in the plane of its section, the hinge line between said upper partition sections extending parallel to and adjacent the hinge line between said lower partition sections; a cross partition section hinged to the upper edge of each of said upper partition sections and hinged at its opposite edge to a carton wall member said upper partition extensions extending downwardly from the cross partition sections, said attachment sections extending between and joining said upper and lower partition sections to form a single central partition.

3. A cellular carton comprising a continuous bottom and lower central partition-forming portion comprising a pair of upwardly extending lower partition sections disposed face to face and hinged together at their upper edges, a bottom section hinged to the lower edge of each of said lower partition sections and hinged at its opposite edge to a carton wall member; and a continuous cross partition and upper central partition-forming portion comprising a pair of downwardly extending upper partition sections disposed face to face and hinged together at their lower edges, the hinge line between said upper partition sections extending parallel to and adjacent the hinge line between said lower partition sections; a cross partition section hinged to the upper edge of each of said upper partition sections and hinged at its opposite edge to a carton wall member; an attachment extension cut out of one of the partition sections of one pair of partition sections adjacent its point of hinging to the other section of said pair and extending in the plane of its section and fixed to the other pair of partition sections to join the partition sections into a central partition.

4. A cellular carton comprising a continuous bottom and lower central partition-forming portion comprising a pair of upwardly extending lower partition sections disposed face to face and hinged together at their upper edges; a bottom section hinged to the lower edge of each of said lower partition sections and hinged at its opposite edge to a carton wall member; and a continuous cross partition and upper central partition-forming portion comprising a pair of downwardly extending upper partition sections disposed face to face and hinged together at their lower edges,

the hinge line between said upper partition sections extending parallel to and adjacent the hinge line between said lower partition sections; a cross partition section hinged to the upper edge of each of said upper partition sections and hinged at its opposite edge to a carton wall member, and a connection joining the pairs of partition sections to form a single central partition.

5. A cellular carton comprising a continuous bottom and lower central partition-forming portion comprising a pair of upwardly extending lower partition sections disposed face to face and hinged together at their upper edges; a bottom section hinged to the lower edge of each of said lower partition sections and hinged at its opposite edge to a carton wall member; and a continuous cross partition and upper central partition-forming portion comprising a pair of downwardly extending upper partition sections disposed face to face and hinged together at their lower edges, the hinge line between said upper partition sections extending parallel to and adjacent the hinge line between said lower partition sections; a cross partition section hinged to the upper edge of each of said upper partition sections and hinged at its opposite edge to a carton wall member.

6. A cellular carton comprising in order, and hinged together, a closure flap, a top, a first side wall, a first bottom section, a first lower partition section, a second lower partition section, a second bottom section, a second side wall, a first cross partition section, a first upper partition section, a second upper partition section, a second cross partition section and an attaching flap, said attaching flap being secured to said first side wall section and said upper partition sections being disposed face to face and extending downwardly from said cross partition sections and said lower partition sections being disposed face to face and extending upwardly from said bottom sections, all forming a continuous partition and being joined together by means of opposed upwardly and downwardly extending attachment extensions cut from certain of said partition extensions adjacent the hinge line between partition sections and extending in the planes of their partition sections and on opposite sides of said continuous partition and secured to one of the opposed partition sections, said extensions being of identical size and being disposed directly opposite and fitting into the cut outs in the opposed partitions from which the opposing extensions were cut.

7. A cellular carton comprising in order, and hinged together, a closure flap, a top, a first side wall, a first bottom section, a first lower partition section, a second lower partition section, a second bottom section, a second side wall, a first cross partition section, a first upper partition section, a second upper partition section, a second cross partition section and an attaching flap, said attaching flap being secured to said first side wall section and said upper partition sections extending downwardly from said cross partition sections and being disposed face to face and said lower partition sections extending upwardly from said bottom sections and being disposed face to face, all forming a continuous partition and being joined together by means of attachment extensions cut from certain of said partition extensions adjacent the hinge line between partition sections and extending in the planes of their partition sections and secured to one of the opposed partition sections.

8. A cellular carton comprising in order, and hinged together, a closure flap, a top, a first side wall, a first bottom section, a first lower partition section, a second lower partition section, a second bottom section, a second side wall, a first cross partition section, a first upper partition section, a second upper partition section, a second cross partition section and an attaching flap, said attaching flap being secured to said first side wall section and said upper partition sections extending downwardly from said cross partition sections and being disposed face to face and said lower partition sections extending upwardly from said bottom sections and being disposed face to face, all forming a continuous partition and being joined together.

9. A cellular carton comprising a continuous bottom and lower central partition-forming portion comprising a pair of lower partition sections disposed face to face and hinged together at their upper edges, one of said lower partition sections having an attachment extension thereon cut out of the other of said lower partition sections adjacent the point of hinging of said sections and projecting upwardly in the plane of its sections; a bottom section hinged to the lower edge of each of said lower partition sections and hinged at its opposite edge to a carton wall member, said bottom sections forming an inverted V and said lower partition sections extending upwardly therefrom; and a continuous cross partition and upper central partition-forming portion comprising a pair of upper partition sections disposed face to face and hinged together at their lower edges, one of said lower partition sections having an attachment extension thereon cut out of the other of said upper partition sections adjacent the point of hinging of said sections and projecting downwardly in the plane of its section and being identical in size and shape with the upwardly extending attachment extension of the lower partition sections, said upper and lower partition sections forming a central partition with the hinge line between said upper partition sections extending parallel to and adjacent the hinge line between said lower partition sections; a cross partition section hinged to the upper edge of each of said upper partition sections and hinged at its opposite edge to a carton wall member said upper partition sections extending downwardly from said cross partition sections, the attachment extensions from the upper and lower partition sections being disposed on opposite sides of the central partition and each disposed directly opposite and fitting in the portion of the opposed partition section from which the other attachment extension was cut and fixed therein, whereby said bottom sections are maintained in their inverted V form.

10. A cellular carton comprising side wall members and a continuous bottom and lower central partition-forming portion comprising a pair of lower partition sections disposed face to face and hinged together at their upper edges; a bottom section hinged to the lower edge of each of said lower partition sections and hinged at its opposite edge to a carton wall member, said bottom sections forming an inverted V and said lower partition sections extending upwardly from the apex of said V; and a continuous cross partition and upper central partition-forming portion comprising a pair of upper partition sections disposed face to face and hinged together at their lower edges, the hinge line between said upper partition sections extending parallel to and adjacent the

hinge line between said lower partition sections; a cross partition section hinged to the upper edge of each of said upper partition sections, and hinged at its opposite edge to a carton wall member; said upper partition sections extending downwardly from said cross partition sections, the combined vertical dimensions of the assembled partition sections being less than the vertical dimension of a side wall member, and a connection joining the pairs of partition sections to form a single central partition, whereby said bottom sections are maintained in their inverted V form.
